UNITED STATES PATENT OFFICE.

HARRY D. EUSTON, OF QUINCY, MASSACHUSETTS.

SHEET-METAL-POLISHING MACHINE.

1,253,675.

Specification of Letters Patent. Patented Jan. 15, 1918.

Application filed June 26, 1916. Serial No. 105,919.

To all whom it may concern:

Be it known that I, HARRY D. EUSTON, a citizen of the United States, and a resident of Quincy, in the county of Norfolk and

5 State of Massachusetts, have invented a new and useful Sheet-Metal-Polishing Machine, of which the following is a specification.

My invention relates to a polishing machine wherein a drum covered with felt, said felt being charged with a suitable abrasive such as pumice, is rotated against a sheet metal plate, said plate being backed up by an idler roll, and fed over the felt covered drum by two sets of feed rollers. These feed 10 rollers and the idler roll have suitable means of adjustment by means of which the amount of pressure between idler and drum may be regulated and by means of which the distance between feed rolls can be changed to 15 compensate for different thicknesses of plates.

My invention particularly relates to a machine for polishing sheet copper such as used in the engraving art and is used preferably 20 on plates which have been planished on my planishing machine, the details of which are substantially described in a previous application.

A complete description of my polishing 25 machine follows, reference being made to the accompanying drawings of which Figure 1 is a side elevation, Fig. 2 an end elevation, and Fig. 3 a diagrammatic section through the main cylinder showing the plate and the 30 relative directions of action of the feed and idler rolls, etc.

The two side frames 1, having a door 1^a to examine interior, are held together by 35 four tie rods 2, holding between them a box like trough 3 of sheet iron, preferably galvanized, having a door 3^a in the bottom for clean-out purposes. Inside this trough and held in position by suitable bearings in the frame, is the main polishing drum 4. 40 This drum is driven by belting from a suitable source of power by the pulley 5.

Rotating at the same surface speed as the main drum 4 is a roll 6, having its outer surface serrated in an axial direction and 45 being held in suitable bearings in the levers 7-7 which in turn are pivoted at one end in the frames 1-1 and held by the tension springs 8-8. The end gudgeons on the roll pass through slots in the frames 1-1, said 55 slots being long enough to let the roll have a little vertical play and to allow the tension

springs 8-8 to hold the roll 6 against the drum 4. The roll 6 is driven from the main shaft by the sprockets 9 and 10 and the chain 11.

On one end of the main drive shaft is a worm 12 which drives the worm wheel 13 which is on a shaft held by suitable bearings cast integral with the frame 1, and has on its upper end a bevel gear 14. This gear 65 drives another bevel gear 15 which is mounted on the horizontal worm shaft 16 which is also held in suitable brackets cast integral with the frame.

Also mounted on the shaft 16 are the 70 worms 17-17 which drive the worms 18-18 which are mounted on the ends of the lower feed rolls 19^a-19 and drive them.

On the upper part of frames 1-1 are guides in which the ends of the upper feed 75 rolls half-boxes 20-20 are held which in turn hold the upper feed rolls 21^a-21 pressed against the sheet metal plate when same is between the upper and lower feed rolls, by means of the hand screws 22-22.

Also held in a suitable guide on top of the frames 1-1 are the idler roll boxes 23 which hold the idler rolls 24 pressed against the main drum 4 by means of the springs 25, the spring holder 26, the adjusting screws 27 80 and the lock-nuts 28.

In operating my polishing machine the main drum 4 is first covered with hard polishing felt about $\frac{1}{2}$ inch in thickness and then some suitable abrasive such as 85 pulverized pumice stone is placed in the bottom of the sheet metal trough 3. The machine is started and the main drum revolves in the relative direction shown by the diagrammatic section Fig. 3. The abrasive is 90 picked up by the longitudinal serrations in roll 6 and a suitable amount is pressed into the felt covering on drum 4. This operation is seen to be continuous as long as the machine is driven by pulley 5. When a plate 100 is to be polished it is inserted into the machine through feed rolls 19^a and 21^a and as the rolls 19^a and 19 are driven through the worms, worm wheels and bevel gears previously described, they move the plate 105 toward the drum 4. In feeding the plate forward it is caught between the drum 4 and idler roll 24 and with the springs 25 adjusted for the right pressure the abrasive action begins and continues until the entire 110 length of plate has passed between the rolls. As the plates polished are always longer

than the distance between the feed rolls 19^a and 21^a, and 19 and 21, other pairs of rolls and therefore is fed positively past the rotating drum 4.

- 5 On some machines there is a piece of steel 29 running from frames 1 across the machine having on its upper surface a strip of soft felt 30, the object being to clean off any minute particles of the abrasive that 10 might tend to adhere to the plate 31, therefore preventing these small particles from being rolled into the plate by the feed rolls 19, 21.

It will be seen that as the drum 4 rotates evenly and that the feed is constant, a plate polished by this machine shows an evenly polished surface and is much superior to the hand buffed plate used in the engraving art.

- 20 What I claim as new is:—

In a sheet metal polishing machine, the combination of a frame, a power operated

felt covered drum mounted on the frame, a serrated cylinder in axial relation to the drum, and driven simultaneously with it, a 25 flexible support for a cylinder which is held against the drum for charging it with an abrasive material, a casing covering the drum and the cylinder the latter serving as a receptacle for the abrasive material, rolls 30 for feeding the sheet metal over the polishing drum, suitable gears for operating the rolls which are driven by the main shaft, adjustable rolls for holding the sheet metal in position and which compensate for the 35 varying thickness of the metal, a wiper secured to the frame for cleaning the abrasive material to prevent it from grinding into the sheet metal plate.
